UNITED STATES PATENT OFFICE.

RUDOLPH CONRADER, OF ERIE, PENNSYLVANIA.

REGULATOR.

SPECIFICATION forming part of Letters Patent No. 775,392, dated November 22, 1904.

Application filed January 29, 1902. Serial No. 91,785. (No model.)

To all whom it may concern:

Be it known that I, RUDOLPH CONRADER, a citizen of the United States, residing at Erie, in the county of Erie and State of Pennsylvania, have invented certain new and useful Improvements in Regulators; and I do hereby declare the following to be a full, clear, and exact description of the invention, such as will enable others skilled in the art to which it applies to make and use the same.

This invention relates to regulators; and it consists in certain improvements in the construction thereof, as will be hereinafter fully described, and pointed out in the claims.

The invention is illustrated in the accompanying drawings, as follows:

Figure 1 shows a plan view, partly in section, on the line 1 1 in Fig. 2. Fig. 2 shows a section on the line 2 2 in Fig. 1. Fig. 3 shows an end elevation from the right of Figs. 1 and 2. Fig. 4 is a partial section on the line 4 4 in Figs. 1 and 2.

A marks the valve-chamber; B, the valve; b, the valve-stem; C, the cover for the valve-chamber, from which project the extension C' and frame C''. The block b' is secured to the stem b. The lever G is pivoted on this block. The lever G is provided with a guide g'', in which is fitted the fulcrum-block g''. The fulcrum-pins g are secured to the block g'' and extend into a sliding yoke g''. The sliding yoke g'' is secured in the guide c. A yoke c' extends from the frame C'', and an adjusting-screw c'' is arranged in this yoke and operates upon the sliding yoke g'', so as to vary the position of the block g'' on the lever G, and consequently the arm of the lever, so that the stem b and valve B are given a greater or smaller movement relatively to the movement of the outer end of the lever G. The outer end of the lever G is pivoted at g'' in a yoke I'.

Extending from the lower end of the yoke I' is the stem i''. This stem rests upon the piston R. The piston R operates in the cylinder L. The cylinder L is provided with the shoulder l'' and is placed in an opening in the extension C''. A cap L' is screwed onto the end of the cylinder, and this, with the shoulder l'', locks the cylinder in the extension

C'. Air or fluid under pressure is admitted 50 to the cylinder L from the chamber M. It enters a chamber k' in the piston, passes through a minute opening k'' to the bottom of the cylinder, and, exerting pressure here on the bottom of the piston, the piston is made 55 to rise and operate the regulating-valve B. Oil is preferably placed in the chamber k', and the opening k'' forms a dash-pot, the opening k'' being small enough for this purpose. A minute opening k' opens into the passage 60 k, and a lateral opening k'' extends from the passage k to the surface of the piston, thus lubricating the piston.

Arranged at the side of the yoke I are the arms I''. The springs I''' connect these arms 65 with the lugs L'', extending from the cylinder L. These springs form a counter-pressure device for the motor formed by the piston K.

A supply-opening m' leads from the cylinder N into the chamber M, and a minute vent 70 m leads from the chamber M to the atmosphere. Arranged in the opening m' is the valve P, with the needle end p. The valve is provided with a cap p' at its end and is secured to a plunger O by means of a flange-nut o, arranged in a cavity o' in the plunger O. The plunger O operates in the cylinder N. The receiver—that is, any receptacle in which the fluid-pressure is regulated—connection N' leads into the cylinder N between the end 75 of the plunger and the supply-opening m'. Extending outwardly from the plunger is a stem O', which engages the lever Q. The mechanism for securing the spring to the lever comprises the adjusting-bolt r and thumb-screws r', by which the bolt may be locked in position. Extending from the lever Q is an arm Q', on which is adjustably mounted the weight Q''. A screw q'' is provided for locking the weight in any position. An arm q 80 extends from the upper end of the lever Q. A set-screw q' is arranged in this arm in position to limit the swinging of the lever Q and the outward movement of the plunger O. A jam-nut q'' is provided for locking the set-screw 85 in an adjusted position.

The operation of the device is as follows: Air being admitted to the cylinder N above

atmospheric pressure exerts pressure on the plunger O. The weight Q² and the initial strength of the spring R are sufficient to hold the valve P seated until the maximum desired pressure of the receiver is reached. When the pressure in the receiver rises above this point, the plunger O is forced outwardly, thus moving the valve P from its seat; but the needle-point remains in the supply-opening m'. The spring R is relatively quite short, so that its strength or tension increases as the plunger moves. Thus the plunger O will occupy a given position with a given receiver-pressure, and a given capacity of opening by the needle-point p is effected. The air passing into the chamber M creates pressure in said chamber. There is a constant escape of air or fluid from the chamber M through the vent m. The pressure in the chamber M, therefore, where the capacity of the supply-opening m' is less than the size of the vent is not very materially increased; but where the supply-opening is made considerably larger through the action of the plunger and the needle-valve then the pressure rises in the chamber M, and consequently in the cylinder L, in proportion to the difference in the relative capacities of the openings m and m'. The springs I⁴ increasing in strength produce a given pressure with a given position of the piston in the cylinder L, so that with a given pressure in the cylinder L the piston K will occupy a certain position in said cylinder, thus giving to the yoke I a certain position, and this acting through the lever G will control the valve B. The extent of movement of the valve B with a given movement of the piston K may be regulated by moving the fulcrum-blocks g³, or the amount of movement of the piston K may be regulated by varying the tension (any convenient means not shown may be used) or length of the springs I⁴. The variation in pressure in the chamber M may be varied by varying the point p of the needle-valve. This may be made more abrupt or more gradual in its taper. Again, this variation in pressure in the chamber M relative to the change of pressure in the receiver may be controlled by adjusting the spring R. Where the desired receiver-pressure is, for example, one hundred pounds and it is desired to keep this within one or two pounds of this pressure, it will be observed that the difference in pressure if directly applied to the piston K would not so overcome the frictional resistances of the parts as to effect a ready response of the piston. By using a secondary motor, as exemplified by the plunger O, with the supply and vent openings and varying the relative capacities of these the pressure operating upon the piston K can be made to vary almost any per cent. desired, with a variation of two or three per cent. in the receiver, so that a positive yet sensitive movement of the

piston can be effected, and consequently closer regulation than is believed to have been practical with devices of this class heretofore constructed. 65

The weight Q² may be dispensed with, if desired, and the entire counter-pressure upon the plunger O be produced by the spring R. The weight Q² does not materially increase in counter-pressure against the plunger O with a movement of the plunger O, while the spring R does this. The adjustment of the weight, 70 therefore, is preferably used to change the moment at which the valve P is open—that is, the receiver-pressure which will bring the regulating device into operation. 75

It will be noted that with the present structure a given receiver-pressure within the limits of pressure desired will maintain the piston K at a practically fixed point so long as the receiver-pressure remains constant. The consequent adjustment of the valve B is 80 such as to give a constant supply to the receiver, so that if the outgo from the receiver remains constant the parts will remain in one position. 85

What I claim as new is— 90

1. In a regulator, the combination of a regulating-valve; a valve-actuating motor arranged to influence the regulating-valve; means for connecting said motor with a fluid-supply, said motor being arranged to act with a change 95 of the fluid-pressure controlled by the regulating-valve; and means for intensifying the change of fluid-pressure on the motor over a change of the fluid-pressure controlled by the regulating-valve. 100

2. In a regulator, the combination of a regulating-valve; a valve-actuating motor arranged to influence the regulating-valve; means for connecting said motor with a fluid-receiver, the fluid-supply of which is to be regulated, 105 said motor being arranged to act with a change of pressure in said connecting means; and means for intensifying the change of fluid-pressure on the motor over a change of pressure in the connecting means. 110

3. In a regulator, the combination of a regulating-valve; a valve-actuating motor arranged to influence the regulating-valve; means for connecting said motor with a fluid-supply, said motor being arranged to act with a change 115 of pressure controlled by the regulating-valve; means for intensifying the change of fluid-pressure on the motor over a change of the pressure controlled by the regulating-valve; and means for controlling the extent of said 120 intensifying action.

4. In a regulator, the combination of a regulating-valve; a valve-actuating motor arranged to influence the regulating-valve; means for connecting said motor with a fluid-supply, 125 the fluid-supply of which is to be regulated, said motor being arranged to act with a change of pressure in said connecting means; means

- for intensifying the change of fluid-pressure on the motor over a change of pressure in the connecting means; and means for controlling the extent of said intensifying action.
5. In a regulator, the combination of a regulating-valve; a valve-actuating motor arranged to influence the regulating-valve; means for connecting said motor with a fluid-supply, said motor being arranged to act with a change 10 of the pressure controlled by the regulating-valve; means for intensifying the change of fluid-pressure on the motor over a change of pressure controlled by the regulating-valve; and means for controlling said intensifying 15 action to vary the pressure on the motor in a fixed ratio to a change in the pressure controlled by the regulating-valve.
6. In a regulator, the combination of a regulating-valve; a motor arranged to influence 20 the regulating-valve; a counter-pressure mechanism arranged in opposition to said motor and varying in strength with the movement of the motor; means for connecting said motor with the fluid-supply; and means for intensifying 25 the change of fluid-pressure on the motor over the change of pressure controlled by the regulating-valve.
7. In a regulator, the combination of a regulating-valve; a motor arranged to influence 30 the regulating-valve; means for connecting said motor with a fluid-receiver, the fluid-supply of which is to be regulated, said motor having a supply-opening from said means of connection and a vent-opening.
35. 8. In a regulator, the combination of a regulating-valve; a motor arranged to influence the regulating-valve; means for connecting said motor with a fluid-receiver, the fluid-supply of which is to be regulated, said motor 40 having a supply-opening from said means of connection and a vent-opening; and means for varying the relative capacities of the supply and vent openings.
9. In a regulator, the combination of a regulating-valve; a motor arranged to influence 45 the regulating-valve; means for connecting said motor with the fluid-receiver, said motor having a supply-opening from said means of connection and a vent-opening; and means for 50 varying the capacity of the supply-opening.
10. In a regulator, the combination of a regulating-valve; a motor arranged to influence the regulating-valve; means for connecting said motor with a fluid-receiver, said motor 55 having a supply-opening from said means of connection, and a vent-opening; and means for automatically varying the relative capacities of the supply and vent openings.
11. In a regulator, the combination of a regulating-valve; a motor arranged to influence 60 the regulating-valve; means for connecting said motor with a fluid-receiver, the fluid-supply of which is to be regulated, said motor having a supply-opening from said means of 65 connection and a vent-opening; and means for automatically varying the relative capacities of the supply and vent openings.
12. In a regulator, the combination of a regulating-valve; a motor arranged to influence the regulating-valve; means for connecting 70 said motor with a fluid-receiver, said motor having a supply-opening from said means of connection and a vent-opening; and means for automatically varying the capacity of the supply-opening.
75. 13. In a regulator, the combination of a regulating-valve; a motor arranged to influence the regulating-valve; means for connecting said motor with a fluid-receiver, the fluid-supply of which is to be regulated, said motor 80 having a supply-opening from said means of connection and a vent-opening; and means actuated by fluid under pressure from said connecting means for varying the relative capacities of the supply and vent openings.
85. 14. In a regulator, the combination of a regulating-valve; a motor arranged to influence the regulating-valve; means for connecting said motor with a fluid-receiver, the fluid-supply of which is to be regulated, said motor 90 having a supply-opening from said means of connection and a vent-opening; means for automatically varying the relative capacities of said openings with a variation of pressure in said connecting means; and means for controlling 95 the extent of variation with a given variation of pressure in said connecting means.
15. In a regulator, the combination of a regulating-valve; a motor arranged to influence the regulating-valve; means for connecting 100 said motor with a fluid-receiver; the fluid-supply of which is to be regulated, said motor having a supply-opening from said means of connection and a vent-opening; means for automatically varying the relative capacities of 105 said openings with a variation of pressure in said connecting means; means for controlling the extent of variation with a given variation of pressure in said connecting means; and means for controlling 110 the extent of variation with a given variation of pressure in said connecting means; and means for adjusting said controlling means to change the extent of variation in the relative capacities of the openings with a given variation in pressure in said connecting means.
16. In a regulator, the combination of a regulating-valve; a motor arranged to influence 115 the regulating-valve; means for connecting said motor with a fluid-receiver, said motor having a supply-opening from said means of connection and a vent-opening; means for automatically varying the capacity of the supply-opening with a variation of a pressure controlled by said regulating-valve; and means for controlling the extent of variation with a given variation of pressure controlled by said regulating-valve.
120. 17. In a regulator, the combination of a regulating-valve; a motor arranged to influence the regulating-valve; means for connecting 125

- 5 said motor with a fluid-receiver, the fluid-supply of which is to be regulated, said motor having a supply-opening from said means of connection and a vent-opening; means for automatically varying the capacity of the supply-opening with a variation of a pressure in said connecting means; and means for controlling the extent of variation with a given variation of pressure in said connecting means.
- 10 18. In a regulator, the combination of a regulating-valve; a motor arranged to influence the regulating-valve; a counter-pressure mechanism varying in strength with a movement of the motor; means for connecting said motor with a fluid-receiver, the fuel-supply of which is to be regulated, said motor having a supply-opening from said means of connection and a vent-opening.
- 15 19. In a regulator, the combination of a regulating-valve; a motor arranged to influence the regulating-valve; a counter-pressure mechanism varying in strength with a movement of the motor; means for connecting said motor with a fluid-receiver, the fluid-supply of which is to be regulated, said motor having a supply-opening from said means of connection, and a vent-opening; and means for varying the relative capacities of said openings.
- 20 20. In a regulator, the combination of a regulating-valve; a motor arranged to influence the regulating-valve; a counter-pressure mechanism varying in strength with a movement of the motor; means for connecting said motor with a fluid-receiver, the fluid-supply of which is to be regulated, said motor having a supply-opening from said means of connection, and a vent-opening; and means for automatically varying the relative capacities of said openings.
- 25 21. In a regulator, the combination of a regulating-valve; a motor arranged to influence the regulating-valve; a counter-pressure mechanism varying in strength with a movement of the motor; means for connecting said motor with a fluid-receiver, the fluid-supply of which is to be regulated, said motor having a supply-opening from said means of connection and a vent-opening; means for automatically varying the relative capacities of the openings with a variation in pressure in said connecting means; and means for controlling the extent of variation with a given variation of pressure in said connecting means.
- 30 22. In a regulator, the combination of a regulating-valve; a regulating-motor arranged to influence said regulating-valve; a controlling-motor; means for connecting said controlling-motor with a receiver; means actuated by said controlling-motor for admitting fluid to said regulating-motor; and means controlled by said controlling-motor for intensifying the pressure on the regulating-motor over a change of pressure in the connecting means.
- 35 23. In a regulator, the combination of a regulating-valve; a regulating-motor arranged to influence said regulating-valve, said motor being provided with supply and vent openings; a controlling-motor; means for connecting said controlling-motor with a receiver; and a valve actuated by said controlling-motor, and arranged to vary the relative capacities of said supply and vent openings.
- 40 24. In a regulator, the combination of a regulating-valve; a regulating-motor arranged to influence said regulating-valve; said motor being provided with a supply and a vent opening; a controlling-motor; means for connecting said controlling-motor with a receiver; and a valve actuated by said controlling-motor and arranged to operate upon the supply-opening to vary the capacity of said opening.
- 45 25. In a regulator, the combination of a regulating-valve; a regulating-motor arranged to influence said regulating-valve, said motor being provided with a supply and a vent opening; a controlling-motor; a counter-pressure device on said controlling-motor arranged to increase in strength with a movement of said motor; means for connecting said controlling-motor with a receiver; and a valve actuated by said controlling-motor, and arranged to vary the capacity of one of said openings with a movement of said motor.
- 50 26. In a regulator, the combination of a regulating-valve; a regulating-motor arranged to influence said regulating-valve, said motor being provided with a supply and a vent opening; a controlling-motor; a counter-pressure device on said controlling-motor arranged to increase in strength with a movement of said controlling-motor; means for connecting said controlling-motor with a receiver; and a valve actuated by said controlling-motor and arranged to vary the capacity of one of said openings with a movement of said motor; and means for adjusting the counter-pressure device to vary the movement of the controlling-motor with a given change of pressure in said connecting means.
- 55 27. In a regulator, the combination of a regulating-valve; a regulating-motor arranged to influence said regulating-valve, said motor being provided with a supply and a vent opening; a controlling-motor; a counter-pressure device on said controlling-motor arranged to increase in strength with a movement of said motor; means for connecting said controlling-motor with a receiver; a valve mechanism actuated by said motor for varying the capacity of one of said openings and for controlling the supply-passage; and means for adjusting the counter-pressure mechanism for varying the movement of the controlling-motor to actuate the valve mechanism to open the supply-passage at different pressures in said connecting means.
- 60 28. In a regulator, the combination of a regulating-valve; a regulating-motor arranged to

- influence said regulating-valve, said motor being provided with a supply and a vent opening; a controlling-motor; a counter-pressure device on said controlling-motor arranged to 5 increase in strength with a movement of said controlling-motor; means for connecting said controlling-motor with a receiver; a valve mechanism actuated by said motor for varying the capacity of one of said openings and 10 for controlling the supply-passage; and means for varying the valve action in the opening to vary the relative capacities of the openings after the supply-passage is opened by the valve mechanism.
- 15 29. In a regulator, the combination of a regulating-valve; a regulating-motor arranged to influence said regulating-valve, said motor being provided with a supply and a vent opening; a controlling-motor; a counter-pressure device on said controlling-motor arranged to 20 increase in strength with a movement of said motor; means for connecting said controlling-motor with a receiver; a valve mechanism actuated by said motor for varying the capacity 25 of one of said openings and for controlling the supply-passage; and means for varying the capacity of the supply-opening after the supply-opening is opened.
- 30 30. In a regulator, the combination of a regulating-valve; a regulating-motor arranged to influence said regulating-valve, said motor being provided with a supply and a vent opening; a controlling-motor; a counter-pressure device on said controlling-motor arranged to 35 increase in strength with a movement of said motor; means for connecting said controlling-motor with a receiver; a valve mechanism actuated by said motor for varying the capacity of one of said openings and for controlling the 40 supply-passage; means for varying the valve action on the opening to vary the relative capacities of the openings after the supply-passage is opened by the valve mechanism; and means for adjusting the mechanism to vary the 45 change in the relative capacity of said opening.
- 31 31. In a regulator, the combination of a regulating-valve; a regulating-motor arranged to influence said regulating-valve, said motor being provided with supply and vent openings; a controlling-motor; means for connecting said 50 controlling-motor with a receiver; and a needle-valve actuated by said controlling-motor and arranged in one of said openings.
- 32 32. In a regulator, the combination of a regulating-valve; a regulating-motor arranged to influence said regulating-valve, said motor being provided with supply and vent openings; a controlling-motor; means for connecting said 55 controlling-motor with a receiver; and a needle-valve actuated by said controlling-motor and arranged in said supply-opening.
- 33 33. In a regulator, the combination of a regulating-valve; the piston K; connections be- 65 tween the piston K, and the regulating-valve whereby a movement of the piston K, influences said regulating-valve; the cylinder L, in which said piston operates; the chamber M, having the vent-opening m , and supply-opening m' ; the cylinder N, to which said supply-opening leads; the receiver connection N', opening into said cylinder; the plunger O, arranged in the cylinder N'; the needle-valve P p, arranged in the supply-opening; the lever Q; connection between said lever and the plunger O; and the spring R, arranged on said 70 lever.
- 34 34. In a regulator, the combination of a regulating-valve; the piston K; connections between the piston K, and the regulating-valve whereby a movement of the piston K, influences said regulating-valve; the cylinder L, in which said piston operates; the chamber M, having the vent-opening m , and supply-opening m' ; the cylinder N, to which said supply-opening leads; the receiver connection N', opening into 80 said cylinder; the plunger O, arranged in the cylinder N'; the needle-valve P p, arranged in the supply-opening; the lever Q; connection between said lever and the plunger O; the spring R, arranged on said lever; and means 85 for adjusting said spring R.
- 35 35. In a regulator, the combination of a regulating-valve; the piston K; connections between the piston K, and the regulating-valve whereby a movement of the piston K, influences said regulating-valve; the cylinder L, in which said piston operates; the chamber M, having the vent-opening m , and supply-opening m' ; the cylinder N, to which said supply-opening leads; the receiver connection N', opening into 90 said cylinder; the plunger O, arranged in the cylinder N'; the needle-valve P p, arranged in the supply-opening; the lever Q; connection between said lever and the plunger O; the spring R, arranged on said lever; and means 95 for adjusting said spring R.
- 36 36. In a regulator, the combination of a regulating-valve; a valve-actuating motor; a lever connecting said motor with said valve; means 100 for changing the arm s of said lever to vary the movement of said valve with a movement of said motor; means for connecting said motor with a fluid-receiver, the fluid-supply of which is to be regulated, said motor being arranged 105 to act with a change of pressure in the receiver; and means for intensifying the change of fluid-pressure on the motor over a change of pressure in the connecting means.
- 37 37. In a regulator, the combination of a regulating-valve; a valve-actuating motor; a lever connection between said motor and said valve; means for varying the arms of said lever to vary the movement of the valve with a given movement of the motor; means for connecting 115 said motor with a fluid-receiver, the fluid-sup- 120
- 125

ply of which is to be regulated, said motor having a supply-opening from said means of connection and a vent-opening.

38. In a regulator, the combination of a regulating-valve; a regulating-motor; a lever connecting said regulating-motor with said valve; means for varying the arm *s* of said lever to vary the movement of the valve with a given movement of the motor; a controlling-motor; means for connecting said controlling-motor with a receiver; and means actuated by said

controlling-motor for controlling the fluid-pressure on the regulating-motor to intensify the change of fluid-pressure on the regulating-motor over a change of pressure in the connecting means. 15

In testimony whereof I affix my signature in presence of two witnesses.

RUDOLPH CONRADER.
